TANDEM CONTROL FOR PRESSES

Angus F. Hanney, Norwood, Ohio, assignor to
The American Laundry Machinery Company,
Norwood, Ohio, a corporation of Ohio

Application April 5, 1935, Serial No. 14,785

9 Claims. (Cl. 68—9)

This invention relates to an improvement in control mechanism for pressing machines of the type generally used in laundry and garment work. More particularly the invention relates 5 to the interconnection of the control mechanisms of two machines and to a tandem arrangement of the controls.

The term tandem control is generally applied to two pressing machines attended by one operator and with the control mechanism so arranged that while performing a closing operation at one machine the remote machine may be opened so as to be ready for the operator to remove the finished work when she arrives 15 there.

My invention provides control mechanism for two presses wherein the usual operation of closing one automatically produces opening of the other. The mechanism is so arranged that an 20 additional operation is necessary at the one press to prevent opening of the other.

My invention provides two pressing machines, each having power means for closing the press and compressing a fluid, and means for using 25 fluid compressed at one press for producing a control operation at the other press.

My invention also provides two pressing machines each having a cylinder and piston motor for producing closing movement and a fluid actuated release means for producing opening 30 movement, means for compressing fluid by press-closing operation of the motor of one press, and means for using that compressed fluid to actuate the release means of the other press.

35 Other novel features and advantages will appear in the accompanying specification taken in connection with the drawing.

The drawing represents a pair of pressing machines in end elevation and partly in section 40 with the control mechanism diagrammatically arranged.

For ease of description I have designated the two pressing machines A and B respectively and since they are alike one only will be described 45 and similar numerals will be applied to the other with the prime suffix.

For illustrative purpose I have shown my invention as applied to pressing machines of the type illustrated, described and claimed in the co-pending application of John P. Singiser, Ser. No. 642,053, filed November 10, 1932. This copending application discloses a frame 10 supporting a stationary pressing bed 11 and pivotally supporting also on a bracket of the frame a head 50 lever 12 which carries a pressing head 13 adapt-

ed to coact with the bed. The head is biased toward open position as shown in press B by a spring 14 connected between the rear end of the head lever and the frame. The head is moved into pressing engagement with the bed by means 5 of a toggle 15 which is moved from broken toward straightened position to close the head upon the bed. For so moving the toggle a fluid actuated cylinder and piston motor 16 is provided having a piston 17 whose piston rod 18 10 is connected to the toggle knuckle. Motive fluid is supplied to motor 16 through conduit 19, check valve 20, port 21, valve casing 22 and passage 23. Valve casing 22 houses a reciprocating piston valve 24 having a stem 25 extending rearwardly through the valve casing. A spring 26 normally biases the valve toward the front of the press as shown in press B, which establishes communication from motor 16 through passage 23 to exhaust port 27 so that motor 16 is normally 20 open to atmosphere. When motive fluid is supplied through conduit 19 from a suitable source, piston valve 24 moves to the position shown in press A thus closing the exhaust port and permitting pressure fluid to enter motor 16 25 through passage 23 to cause a working stroke of the motor. Moving in unison with the piston rod 18 is a cam 28 having a depressed portion 29 in which a follower 30 is adapted to drop biased by a spring 31a when the press is substantially completely closed. This establishes a fluid 30 maintaining circuit which maintains the press closed under pressure. The connections for establishing this circuit comprise a bellcrank 31, one arm of which carries the follower 30 and 35 an upstanding arm 32 of which engages the stem 33 of a normally closed inlet valve 34 which is housed in a valve casing 35 and supplied with motive fluid through a suitable conduit 36. This mechanism opens valve 34 when follower 30 40 drops into the depressed portion of the cam 28 and permits motive fluid to pass through conduit 37 to passage 23 which serves to retain valve 24 in the position shown on press A and holds piston 17 at the outermost point of its stroke so 45 that the press remains closed under pressure.

The release mechanism comprises a treadle 38 pivotally mounted on the frame and biased in its upward position by a spring 39. The treadle is connected by a link 40 with a bellcrank 41 50 which has an upstanding arm 42 which lies opposite the valve stem 25 and in position to abut and move the same upon depression of the treadle and rotation of bellcrank 41 in a clockwise direction as seen at press A. At the same 55

time, the arm 42 of the bellcrank is adapted to engage a projection 43 on bellcrank 31 to rotate the bellcrank in a clockwise direction about its pivot thus permitting valve 34 to return to its normally closed position under the influence of its spring. This cuts off the supply of motive fluid to motor 16 and opens the same to exhaust port 27 whereupon spring 14 is effective to reopen the press.

10 The purpose of check valve 20 is to prevent back flow through conduit 19 after the press is fully closed and the maintaining circuit is established.

15 Power means is provided to actuate the treadle 38 and the form shown comprises a small fluid motor 45 whose piston 46 has a stem 47 adapted to coat with the upstanding arm 48 of treadle 38 so as to move the treadle in a clockwise direction about its pivot. The piston is biased toward inoperative position by a spring and is supplied with motive fluid through a suitable conduit 49. The piston 46 is sufficiently loose-fitting to permit its return movement by its biasing spring.

20 My improvement comprises a novel interconnection of the control mechanism for two such presses as shown in the drawing. For the supply of motive fluid to motor 16 I provide two normally closed inlet valves 50 and 51 in series with a supply conduit 52 communicating with the main conduit 36 and a conduit 53 connecting the two valves in series. Valve 50 is actuated by manual 54 and valve 51 by manual 55 and it will be evident that actuation of both manuals simultaneously will supply motive fluid to conduit 19 and motor 16 as previously described.

25 Means is provided whereby the normal actuation of the control means for press A energizes the power actuator for the release means of press B. This comprises the arrangement of the rear end of the cylinder and piston motor 16 in a manner to compress air or other fluid before the advancing piston during the early portion of the press closing stroke of piston 17. To this end the piston rod 18 and the portion of cam bar 28 of larger section slidably engage suitable openings in the cylinder head 56, the opening for accommodating the cam bar being designated 57. Thus with the parts in the position shown at press B the rear end of the cylinder is substantially fluid tight and the advancing piston will compress air therein. A conduit 58 establishes communication from the rear end of the cylinder of motor 16 to the release motor 45' at the other press.

30 In the normal operation of the machines A and B in tandem the press A being open and the press B closed, the operator would arrange the lay of the work upon the bed 11 and actuate manuals 54 and 55. This would supply motive fluid to motor 16 which would close the press as already described and during the first portion of the press closing stroke of piston 17, fluid compressed at the rear end of the cylinder would travel through conduit 58 to motor 45' and cause a stroke of piston 46' which would cause press opening movement of machine B as already described. This compressed fluid trapped behind piston 17 causes a snubbing action of the press closing movement. During the latter portion of the stroke of piston 17 the reduced portion 29 of cam bar 28 enters opening 57 in the rear cylinder head so that this opening is now only partially closed and the compressed fluid behind piston 17 is enabled to escape to the atmosphere. With the release of the pressure

through opening 57 this press closing movement continues rapidly to completion. At the same time motor 45' is evacuated through conduit 58 and opening 57.

35 Means is provided whereby the operator may prevent the release operation at the other press when desired. This comprises a conduit 59 branching from conduit 58 and leading to a normally closed outlet valve 60 which is operable by manual 61. This manual may be located 40 in any preferred position but a very efficient arrangement is the location of manual 61 adjacent one of the manuals 54 or 55 so as to be grasped simultaneously by one hand of the operator. In the drawing, manual 61 is located adjacent 45 manual 55 and upon movement of the manuals 54 and 55 in press closing direction manual 61 may be grasped to open valve 60. This provides sufficient release for the air compressed before the advancing piston 17 so that insufficient pressure is built up in conduit 58 to actuate release motor 45' at press B.

40 What I claim is:

1. Two independently operable presses arranged for tandem operation by a single operator, each press having a pair of coacting relatively movable pressing members, power means at each press for relatively moving said members for a pressing operation, each of said power means being arranged to compress fluid during 45 its press-operating motion, a fluid actuated device at each press for causing operation thereof, and means for conducting said fluid compressed at one press to said device at the other press, whereby operation of one press causes simultaneous operation of the other press.

2. Two independently operable presses arranged for tandem operation by a single operator, each press having a pair of coacting relatively movable pressing members, a cylinder and 40 piston motor at each press for relatively moving said members for a pressing operation, said motor being arranged to compress fluid by a stroke of its piston, a fluid actuated device at each press for causing operation thereof, and means for conducting said fluid compressed at one press to said device at the other press, whereby operation of one press causes simultaneous operation of the other press.

3. In combination, two independently operable presses arranged for tandem operation by a single operator, a cylinder and piston motor for closing each press, each motor being arranged to compress fluid by a press-closing stroke of its piston, fluid actuated release means for causing 55 opening of each press, control means for each motor, and conduit means for conducting said compressed fluid at each press to the release means of the other press.

4. In combination, two independently operable presses arranged for tandem operation by a single operator, a cylinder and piston motor for closing each press, each motor being arranged normally to compress fluid by a press-closing 65 stroke of its piston, control means for each motor, fluid actuated release means for causing opening of each press, conduit means for conducting said compressed fluid at each press to the release means of the other press, and operator controlled means at each press for preventing compression of fluid by said piston stroke.

5. In combination, two independently operable presses arranged for tandem operation by a single operator, a cylinder and piston motor for closing each press, each motor being arranged 75

normally to compress fluid by a press-closing stroke of its piston, control means for each motor including two spaced safety manuals, fluid actuated release means for causing opening of each 5 press, conduit means for conducting said compressed fluid at each press to the release means of the other press, and operator controlled means at each press for preventing compression of fluid by said piston stroke, said last named 10 means including a control member grouped with one of said manuals.

6. In combination, two independently operable presses arranged for tandem operation by a single operator, a cylinder and piston motor for 15 closing each press, each motor being arranged to compress fluid by a press-closing stroke of the piston, fluid actuated release means for causing opening of each press, control means for each motor, conduit means for conducting said 20 compressed fluid at each press to the release means of the other press, a normally closed exhaust valve in each of said conduit means, and operator-controlled means for opening each of said valves to release said compressed fluid.

25 7. In combination, two independently operable presses positioned for tandem operation by one operator, a cylinder and piston motor for closing each press, fluid means for advancing each piston for a press-closing operation, each 30 motor being arranged to trap and compress fluid in said motor in advance of its piston, fluid actuated release means for causing opening of each press, conduits for conducting said compressed fluid from each motor at one of said 35 presses to the release means of the other of said presses, and means for opening each of said conduits to atmosphere.

8. In combination, two independently operable 40 presses arranged for tandem operation by a single operator, each having a pair of coacting pressing members one of which is movable toward and from the other to close and open the

press, a cylinder and piston motor having its piston rod operatively connected to the movable pressing member to move it to press-closed position, the end of said cylinder opposite the motive end being substantially air tight to trap and 5 compress air before the advancing piston, fluid actuated release means for opening each press, a conduit adapted to conduct compressed air from the motor of each press to the release means of the other press, a cam bar on each 10 motor movable with and substantially parallel to the piston rod thereof, said cam bar having a reduced section at its end nearer the piston and at its other end having a substantially air tight sliding fit in an opening through the cylinder 15 head, maintaining means for holding each press closed, and said maintaining means having an operative connection with a follower adapted to engage said reduced cam bar section upon press-closing movement of said motor sufficient to 20 move said pressing members to safe-closed position, whereby, during a press-closing stroke of a motor at each press, air is first compressed ahead of its advancing piston for snubbing the closing movement of that press and for actuating release 25 means at the other press, and during the latter part of the piston stroke the compressed air is released by said reduced cam bar section entering said opening.

9. Two independently operable presses ar- 30 ranged for tandem operation by a single operator, each press having a pair of coacting relatively movable pressing members, power means at each press for relatively moving said members to close the press, each of said power means being arranged to compress fluid during its press-closing motion, release means for causing opening of each press, a fluid actuator for each release means, and conduit means for conducting said compressed fluid at each press to the re- 35 lease actuator of the other press.

ANGUS F. HANNEY.
